(57) **CLAIM**

The ornamental design for a handheld fan, as shown and described.

DESCRIPTION

FIG. 1 is a perspective view of a handheld fan showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of the handheld fan shown within the area designated as 9 in FIG. 1; and,

FIG. 10 is an enlarged view of the handheld fan shown within the area designated as 10 in FIG. 2.

The broken lines in the drawings are for the purpose of illustrating portions of the handheld fan that form no part of the claimed design.

1 Claim, 10 Drawing Sheets
